(57) **CLAIM**

The ornamental design for a phone accessory, as shown and described.

DESCRIPTION

FIG. 1 is a top front perspective view of an embodiment of a phone accessory, illustrating the phone accessory in an open position and attached to an example phone;

FIG. 2 is a top front perspective view of the phone accessory of FIG. 1, illustrating the phone accessory in a closed position and attached to an example phone;

FIG. 3 is a front view of the phone accessory of FIG. 1;

FIG. 4 is a rear view of the phone accessory of FIG. 1;

FIG. 5 is a right side view of the phone accessory of FIG. 1;

FIG. 6 is a left side view of the phone accessory of FIG. 1;

FIG. 7 is a top view of the phone accessory of FIG. 1;

FIG. 8 is a bottom view of the phone accessory of FIG. 1;

FIG. 9 is a top front perspective view of another embodiment of a phone accessory, illustrating the phone accessory in an open position and attached to an example phone;

FIG. 10 is a top front perspective view of the phone accessory of FIG. 9, illustrating the phone accessory in a closed position and attached to the example phone;

FIG. 11 is a front view of the phone accessory of FIG. 9;

FIG. 12 is a rear view of the phone accessory of FIG. 9;

FIG. 13 is a right side view of the phone accessory of FIG. 9;

FIG. 14 is a left side view of the phone accessory of FIG. 9;

FIG. 15 is a top view of the phone accessory of FIG. 9; and,

FIG. 16 is a bottom view of the phone accessory of FIG. 9.

The broken lines are shown for the purpose of illustrating environmental structure and parts of the article that form no part of the claimed design.
